(57) **CLAIM**

The ornamental design for a handle, as shown and described.

DESCRIPTION

FIG. 1 is a perspective view of a handle, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of one embodiment of my new design for a handle;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof;

FIG. 14 is a bottom plan view thereof;

FIG. 15 is a perspective view thereof, showing the handle in use as part of a handbag, where the handle includes an optional logo, the logo forming no part of the claimed design; and,

FIG. 16 is a top plan view of the handle in the embodiment shown in FIG. 15.

The lightweight, short broken lines in the drawings illustrate features of the handle and the environment which form no part of the claimed design.

In FIGS. 1-7, the handle is shown with symbolic breaks. The appearance of any portion of the handle between the break lines forms no part of the claimed design.
